(57) **CLAIM**

The ornamental design for jar, as shown and described.

DESCRIPTION

FIG. 1 is a perspective view of a jar embodying our new design;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof, the left side elevational view being a mirror image; and,

FIG. 7 is a cross sectional view thereof, taken at section line 7—7 as shown in FIG. 2.

The broken lines shown in the drawing views are included for the purpose of showing environmental structure that forms no part of the claimed design.

The cap is translucent.
